UNITED STATES PATENT OFFICE

157,829

TIRE

Philip E. Bergen, Farmington, Conn.

Application January 11, 1949, Serial No. 163

Term of patent 14 years

(Cl. D90—20)

To all whom it may concern:

Be it known that I, Philip E. Bergen, a citizen of the United States, residing at Farmington, in the county of Hartford and State of Connecticut, have invented a new, original, and ornamental Design for a Tire, of which the following is a specification, reference being had to the accompanying drawing, forming part thereof.

Fig. 1 is a fragmentary plan view of a tire showing my new design.

Fig. 2 is a fragmentary sectional view thereof on line 2—2 of Fig. 1.

Fig. 3 is a fragmentary sectional end view thereof on line 3—3 of Fig. 1.

I claim:

The ornamental design for a tire, substantially as shown.

PHILIP E. BERGEN.
